Frank S. Greene
ATTORNEY

UNITED STATES PATENT OFFICE

DANIEL K. POPE, OF CLEVELAND, OHIO

FASTENER FOR SPRING COVERS

Application filed March 11, 1929. Serial No. 345,971.

This invention relates to covers for vehicle springs and more particularly to covers of flexible waterproof material which enclose the spring and retain a pad of felt or similar absorbent material containing a lubricant in contact with the overlapping leaves of the spring.

A serious difficulty heretofore encountered in the use of such spring covers has been that the fabric cover tends to become slack and baggy after it has been in service for some time due to the fact that the continual flexing of the spring causes the lubricating pad to be gradually compacted and reduced in volume so that the cover becomes loose, losing its neatness of appearance and becoming ineffective to prevent entry of moisture to the spring.

The present invention has for one of its main objects to provide a fastening means for the cover which will automatically take up the slack in the cover and which will maintain a substantially uniform tension on the fabric of the cover as long as the cover is in service.

A further object is to provide a spring take-up fastener which will not lose its tension and which will not become detached from either edge of the cover, as the edges are drawn closely together by the fastening means.

A further object is to provide a fastener which will permit attachment of the cover to a spring or detachment of the cover from the spring with a minimum of labor.

A further object is to provide a fastener which is inexpensive to manufacture and which may be quickly and easily applied to the cover.

With the above and other objects in view, the invention may be said to comprise the spring cover as illustrated in the accompanying drawings hereinafter described and particularly set forth in the appended claims, together with such variations and modifications thereof as will be apparent to one skilled in the art to which the invention appertains.

Reference should be had to the accompany-

ing drawings forming a part of this specification in which:

Figure 1 is a side elevation showing the spring cover attached to a vehicle spring.

Fig. 2 is a bottom plan view of a spring with the cover attached thereto.

Fig. 3 is a section taken on the line indicated at 3—3 in Fig. 1.

Fig. 4 is a fragmentary bottom plan view on an enlarged scale showing one of the fasteners connecting the edges of the cover.

Fig. 5 is a perspective view showing one of the fasteners detached.

Referring to the accompanying drawings, the vehicle spring to which the cover is attached is indicated by the reference numeral 1, the fabric cover by the reference numeral 2 and the lubricating pad of felt or other suitable absorbent material impregnated with a lubricant is indicated by the reference numeral 3.

The fabric cover 2 has one edge turned back against the inner side thereof to provide a loop 4 along said edge and the turned-back edge is secured to the body of the cover by a seam 5. A rod 6 extending the full length of the cover is secured in the loop 4.

The cover is made of a width such that it can be wrapped about the spring and pad with its edges overlapping along the bottom of the spring. As shown in Fig. 3 of the drawing, the loop 4 carrying the rod 6 overlies the opposite edge of the cover which lies flat against the bottom of the spring 1. A fabric loop 7 which extends the full length of the cover is attached to the body of the cover by means of a seam 8 and extends parallel with the loop 4, the loop 7 being attached to the edge portion of the cover opposite that

having the loop and being spaced a sufficient distance from said edge to extend along the under side of the spring alongside and spaced from the loop 4. The loop 7 has secured therein a rod 9 which extends the full length of the cover, the rods 6 and 9 serving to reinforce the edge portions of the cover and to provide means of attachment for the fastening devices which will now be described.

The edges of the cover are detachably secured together by means of spring fastening

devices which are indicated generally by the reference numeral 10, a suitable number of these spring fasteners being provided along the length of the cover.

- 5 Referring to Figs. 4 and 5 of the drawing, each fastener is formed of a single piece of spring wire which is bent intermediate its ends to form a coil 11, which may be provided with a sheet metal clip 12 to hold the turns of 10 the coil against separation. The spring wire fastener has opposite end portions forming arms 13 and 14 projecting in the same general direction from the opposite sides of the coil 11, the arm 14 being biased toward a position in which it extends at an angle to the arm 13.

The arm 13 of the fastener has a coil 15 whose axis is disposed at right angles to the axis of the coil 11 and terminates in a laterally projecting end 16. The arm 14 is bent outwardly from the plane of the coil 11 to provide an actuating shoulder 17 and inwardly from the shoulder 17 to provide an inwardly extending portion 18 which terminates in a hook 19. The fabric loop 7 is provided along the length thereof with notches 20 to receive the coils 15 of the fastener and the fasteners are assembled on the rod 9 by threading the rod through the loop 7 and 25 through the coils 15 of the fasteners positioned in the notches 20. The body of the cover 2 is provided with apertures 16 through which the projecting end 16 of the fastener may be inserted so that the end 16 may bear 30 directly upon the under face of the vehicle spring.

When the fastener is assembled on the cover, the ends 16 project from the rod 9 toward the outer edge of the cover and toward 40 the rod 6 when the cover is in place on the spring. The coil 11 lies on the side of the arm 13 of the fastener opposite the projecting end 16 so that when the cover is in place on the spring, the end 16 bearing against 45 the spring tends to rock the coil 11 against the under side of the cover and hold the fastener in operative position.

The loop 4 is provided with notches 22 which are so positioned along the length of 50 the cover as to expose portions of the rod 6 for engagement by the hook 19 of the fastener. The projecting end portion 16 engaging the spring and the loop 11 engaging the cover serve to hold the fastener in a position parallel with the under side of the spring so that by pressing the arm 14 inwardly, the hook 19 may be readily engaged with or disengaged from the rod 6.

55 The outwardly projecting shoulder 17 at the outer end of the arm 14 provides a finger hold on the fastener so that the arm 14 may be quickly and easily pressed toward the rod 9 to move the portion 18 over the space between the rods 6 and 9 and to engage

the hook 19 with or disengage the hook 19 from the rod 6.

Since the fastener is made of relatively stiff spring wire and the arm 14 is biased to swing outwardly away from the rod 9, it will 70 be apparent that when the arm 14 is swung inwardly through a sufficient angle to engage the hook 19 with the rod 6, the arm 14 will be under spring tension and will maintain a constant and substantially uniform 75 pull on the rod 6 so that the fabric of the cover will be kept taut as the absorbent pad is compacted. The cover will be made of a size such that initially, there will be a sufficient space between the loops 4 and 7 to permit the necessary take-up to compensate for shrinkage of the pad and it will be apparent 80 that the spring tension will be maintained upon the cover, even though the loops 4 and 7 be drawn substantially into engagement 85 one with the other.

In applying the cover to the spring, it is necessary simply to wrap the cover around the spring and fasten the edges together by pushing the arms 14 of the fasteners inwardly until the hooks 19 are brought into engagement with the rod 6, and to remove the cover, the fasteners may be disengaged by simply moving the arms 14 inwardly a sufficient distance to release the hooks 19, the 90 fastener being movable about the rod 9 as a pivot to lower the hook 19 into engagement with the rod 6 or to raise the hook 19 clear of the rod 6.

It will be apparent that the present invention provides a simple and inexpensive 100 spring fastener which is permanently attached to the cover and which will effectively take up any slack in the cover while the cover is in service and that this fastening device enables the cover to be assembled on the spring or to be removed from the spring with a minimum of manual labor.

What I claim is:

1. The combination with a cover for vehicle springs composed of flexible material and adapted to be wrapped about the spring with its opposite edges extending along the under side of the spring, of a cover tensioning fastener composed of a piece of spring wire having a coil intermediate its ends and opposite end portions projecting laterally from opposite sides of the coil, one of said end portions being attached to one edge portion of the cover and the other of said end portions being bent inwardly and terminating in a hook engageable with the opposite edge portion of the cover.

2. The combination with a cover for vehicle springs composed of flexible material and adapted to be wrapped about the spring with its opposite edges extending along the under side of the spring, of rods secured to opposite edge portions of the cover and extending longitudinally thereof along the 130

under side of the spring, and a plurality of cover tensioning fasteners, each pivotally mounted on one of said rods and having a resilient arm terminating in a hook engageable with the other rod, said arm being biased toward a position in which it lies to the outer side of the rod on which said fastener is mounted, and means for limiting the pivotal movement of each fastener on its rod.

10. 3. A cover for vehicle springs composed of a piece of flexible material of a size and shape to wrap about the spring with the edges of the cover overlapping along the under side of the spring, one edge of the cover being provided with a reinforcement extending substantially the full length thereof, the opposite edge portion of the cover underlying the reinforced edge and having a longitudinal reinforcement substantially parallel 20 with the reinforced edge, and a plurality of cover tensioning fasteners each attached to one of said reinforcements, and each having a resilient arm terminating in a hook detachably engageable with the other reinforcement, each arm being biased toward a position in which it lies to the outer side of the reinforcement to which it is attached.

In testimony whereof I affix my signature.
DANIEL K. POPE.
